(57) **CLAIM**

The ornamental design for a protection mask for the face, as shown and described.

DESCRIPTION

FIG. 1 is a front elevational view of a protection mask for the face showing my new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left side perspective view thereof;

FIG. 8 is a back, left side perspective view thereof; and,

FIG. 9 is an exploded view thereof.

The broken lines are included for the purpose of illustrating portions of the protection mask for the face that form no part of the claimed design.

1 Claim, 9 Drawing Sheets
